UNITED STATES PATENT OFFICE.

ROBERT G. BROWN, OF SWARTHMORE, PENNSYLVANIA, AND JOHN E. STRIETELMEIER,
OF CINCINNATI, OHIO; SAID BROWN ASSIGNOR TO SAID STRIETELMEIER.

AUTOMATIC REPEATER.

1,413,554.

Specification of Letters Patent. Patented Apr. 18, 1922.

Application filed November 17, 1916, Serial No. 131,842. Renewed October 15, 1921. Serial No. 508,049.

To all whom it may concern:

Be it known that we, ROBERT G. BROWN and JOHN E. STRIETELMEIER, both citizens of the United States, and residing at

5 Swarthmore, in the county of Delaware and State of Pennsylvania, and at Cincinnati, in the county of Hamilton and State of Ohio, respectively, have invented a new and Improved Automatic Repeater, of which the

10 following specification is a full disclosure.

This invention relates to phonograph repeating mechanism and it aims to effect an improvement on the mechanism disclosed and claimed in the co-pending application 15 of Brown and Strietelmeier No. 120,302, filed September 15, 1916, whereby said mechanism is universally applicable to various types and varieties of phonographs without necessitating special elements or fixtures adaptable for 20 given machines only.

Other objects will be in part obvious from the annexed drawings and in part indicated in connection therewith by the following analysis of this invention.

25 This invention accordingly consists in the features of construction, combination of parts and in the unique relations of the members and in the relative proportioning and disposition thereof; all as more completely 30 outlined herein.

To enable others skilled in the art so fully to comprehend the underlying features thereof that they may embody the same by numerous modifications in structure and relation contemplated by this invention, drawings depicting a preferred form have been 35 annexed, as a part of this disclosure, and in such drawings, like characters of reference, denote corresponding parts throughout all 40 the views of which:—

Fig. 1 is a plan of a conventional phonograph having this fixture combined therewith, and showing the davit in overhanging relation with the free end of the tone-arm, and with the trip-lever located in its 45 normal position about to be tripped by impact of the stylus.

Fig. 2 is the side elevation of the same showing the operating mechanism in section along line 2—2 of Fig. 1.

Fig. 3 is a section along line 3—3 of Fig. 1, and Fig. 4 is a section along line 4—4 of Fig. 1.

In general, this invention contemplates a 55 low, compact self-contained device adapted

to enter into combination with the conventional elements of a standard phonograph to function as above-named, and specifically it embraces all or many co-ordinated sub-combinations including (A) a sound-box 60 lifter, which at appropriate intervals lifts and lowers the stylus; (B) a tone-arm shifter which carries the stylus from the end to the beginning of the record; (C) a motion-transmission which furnishes the necessary 65 gears and shifts resulting in an actuation of the lifter and shifter; (D) a power connector which is in the nature of a clutch-mechanism and which at appropriate intervals connects the transmission with the primary 70 source of power, which may preferably be the turn-table itself but which may be any easily accessible motor-driven element; (E) a trip-system which is effective automatically to throw the power connector into 75 action at the appropriate station in the record; (F) a control-lever which automatically effects a disconnection of the power-connector and normalizes the relation of the trip to the mechanism; (G) an adjustor which 80 predetermines the number of times the mechanism operates to replay the record; and (H) a brake which is conveniently caused to operate to conclude the performance.

The chief difficulty with the mechanisms 85 that we have heretofore devised is that they require special fixtures or alterations in detail to adapt them to different makes of phonographs. This occasions much trouble for a purchaser, but we have finally developed a construction readily applicable in a universal way to practically all phonographs having free swinging-arms.

The improvement for achieving this particular result lies principally in the unique 95 arrangement of the lifter and shifter for the tone-arm, and this will now be described:

The base or frame is designed to be made 100 preferably from a single sheet-metal stamping formed in such a manner that the elements are all, or in the main, thin in the horizontal planes, i. e., they are arranged horizontally flat-wise so as not to be very high in the aggregate even when they are superimposed. A unique simplification in 105 structure is shown by the drawings in which the stamping 15 is formed to present a closed top or dome, and an open bottom adapted to receive the "works"; thereby dispensing with the necessity of employing an extra 110

element as a top or cover, together with its fastenings. This one-piece stamping 15 provides two opposite tongues, D and E, providing slots d and e which are elongated 5 in a direction away from the turn-table to aid in ultimately accurately locating the attachment. The stamping also provides positioning pins or tongues B and C which, during the initial adjusting of the device to 10 the phonograph, are first pressed against the edge of the turntable, and the screws are then inserted in the far ends of the slots; but, before they are tightened down finally, the device is then pulled as far away from 15 the turn-table as the length of the slots will permit; and then when the screws are tightened down, the device will be accurately located. The base also provides an ear 9' which is bent inwards and has a hole regis- 20 tering with a hole in the upper part of said base 15 forming a cover, and said holes are adapted to receive a post 9 which supports the davit 11. A bracket N is secured to the side of the base-frame by screws 20' 25 and has two ears 20 extending therefrom which serve to position and act as a bearing for a shaft which is the axis of swing of the sub-frame used for shifting the power off and on. An upward extension 21 and 30 the opening 22 in the end of the base-frame act as guides and bearings for the shiftable brake element shown in Fig. 1.

The stylus lifter and shifter proposed by this invention is universal in its applicability 35 to various types of tone-arms and their sound-boxes. That is to say, in certain types of phonographs the tone-arm and sound-box constitute a rigid unit which, at a point remote from the record, is supported by a uni- 40 versal joint. In other types, the tone-arm swings about a fixed vertical axis at its rear, and the sound-box pivots about a definite horizontal axis at the free-end of the tone-arm. The stylus lifter and shifter herein 45 proposed applies equally well to either type, and for the purposes of this disclosure, it will suffice to explain it in its relation to the latter type. Thus, the tone-arm 4 is here shown as pivoted at its rear end to swing about a 50 vertical axis. A sound-box 2 is pivoted to the free-end of the tone-arm 4 so as to swing up and down about a horizontal axis. This sound-box carries the stylus 3 which normally rides in the groove of the record. It 55 may be explained that when the sound-box 4 is lifted to raise the stylus, it must not begin the swing back until the stylus has entirely cleared the record, otherwise it would be scratched. The lifting and shifting 60 means embodies a davit 11 which is at its upper end journaled in the fixed post 9 which rises from the base. The lower end of the davit 11 is also journaled in the end of a shiftable arm 16; the normal relation of 65 these parts being such that the axis deter-

mined by the upper point e and the lower point k is inclined from the vertical. The upper end of the davit provides an extension or arm 11' which projects outwardly and terminates above the sound-box 2 and is connected therewith by means of a cord or other member 12 so that it may lift the stylus from the groove and return the same to its initial position. 70

The construction herein proposed is such 75 that it will come effectively into action only after the stylus has been raised and in this particular embodiment great simplicity has been attained by intimately incorporating this means with the stylus-lifter, and this has 80 been done by a peculiar relation between the axes e—k and 4' of the davit and tone-arm, respectively. That is to say, when the stylus is free from the record groove and thus exercises a downward pull on the free-end of 85 the davit arm 11', the davit tends to swing about its inclined axis into the particular position in which its free-end will be at its lowest point. Since the pull is vertically downward, it will be in its lowest point when 90 it coincides with the vertical plane determined respectively by the two points e and k. Hence, by adjusting the position of the point e, the vertical plane determined thereby can be caused to lie outside of the initial 95 starting groove of the record, with the effect that when the stylus is uplifted, the davit together with the tone-arm will tend to gravitate to the starting point. To enable this adjustment to be made to conform readily to 100 the requirements in each particular case, the post 9 is so mounted in the base that it may be swung about its vertical axis and fixed in any predetermined position desirable for locating the pivot e. 105

In order that the record may not be scratched by a shifting of the stylus before it is raised clear off the groove, it is desirable that no great turning moment should be imposed on the same at the instant it is uplifted and, to that end, the plane vertically defined by the points e and k should at the instant of lifting be not too remote from the end of the record groove. In other words, this plane should shift or swing from a position near the end of the record groove to a position beyond the record groove after the stylus has been lifted. This result is achieved by effecting a shifting of the pivotal point k after it is moved to lift the stylus. Thus, in 110 this embodiment, the arm 16 is pivoted at a point r to the base 15 with the result that its free-end swings the point k about an arc and thereby effects a progressive variation in the relation between the pivotal points e and k 115 with the result that the stylus is first uplifted without being too strongly urged laterally, and is then subjected to a sufficient lateral force to bring it to its starting position, and this peculiar relation of parts car- 120 125 130

ries the advantage that a single means is enabled to perform the two-fold function of lifting and shifting the stylus in a manner so graduated as not to scratch the record.

5 The motion transmission is the mechanism or train of elements that results in the actuation of the stylus-replacing means by power derived from some motor driven part, such as the turn-table 1; and which preferably embodies reduction gears so that the ultimate motion will be slow and deliberate and the stylus will be handled gently and without jerks and thus save the record from scratches. In this embodiment, this transmission is in 10 part stationary, and in part is bodily shiftable for power connecting purposes. The stationary part comprises a shaft 19 pivoted at its lower end in the ears 20 of the supporting member N which, by means of screws 20^a, is fastened to the side of the main frame. The upper end of this shaft 19 is provided with an eccentric pin 19^a which is connected with the end of the arm 16 by means of the link 17 whereby the davit 11 may be rocked 25 slowly. This shaft 19 derives motion from the clutch element or wheel 29 through a train of reduction gears 24, 25, 26 and 27, the shafts of which are all pivoted to the side plates 23 of a rocking-frame. This rocking-frame is in the nature of a sub-frame composed of a sheet-metal stamping. Both gear-sets 24-25, 26-27 have a pronounced reduction effect with the consequence that the 30 crank pin 19^a is but very slowly turned, although the friction wheel 29 may rotate several times during each revolution of the turn-table.

The power connector is an arrangement in the nature of a clutch and it enables the turn-table to operate during the normal playing of a record without any concomitant operation of the return mechanism. Preferably this means is located so as to disconnect as many parts as possible from the source of motion, to avoid needless wear or noise, and preferably the wheel 29 is therefore entirely withdrawn from the turn-table. This is conveniently done by pivoting the plates 23 of the sub-frame to the shaft 19 so that the 45 shaft 28 of the friction wheel will be carried by the remote free-swinging portion of the sub-frame. The sub-frame is, during the normal playing of a record, held withdrawn by latch means; but, whenever the end of the 50 record is reached, it swings towards the turn-table with the result that the stylus lifter and returner is caused to operate. The position of this sub-frame is in turn determined by the following arrangement:

55 The lever control for the swinging power connector functions first to unlatch and resiliently swing the sub-frame to bring the friction wheel 29 into engagement with the periphery of the turn-table and to maintain 60 this engagement until the tone-arm has been

shifted to its initial point, and in the meanwhile to effect a relatching of the control-lever, and then through the same lever to withdraw the friction-wheel and permit the record to be played without interference. 70 This triple action is very easily effected by the multiple-fulcrum lever-system comprising a sheet-metal lever 31 which is permanently pivoted at 30 to the plate 23 of the swinging sub-frame and which (in the position of the parts shown by Fig. 1) can (when unlatched) be turned about the stationary fulcrum point 19 by acting through the flat edge 18^a of the cam plate 18. That is to say, the hook-like end of the lever 31 80 has entered a right-angle notch 32 in the cam-plate 18 so that it may rest against the edge 18^a thereof which, in a sense, constitutes a stationary fulcrum enabling the lever 31 at the point 30 to pry the plate 23 around 85 the axis 19. Normally, the lever is precluded from this movement by means of a detent 33 which engages with a shoulder 34 of a latch 35 pivoted at 36 to a frame-element and spring-pressed into position by the pull 90 of the spring 38 at the end of the arm 31^a. The rotation of the cam 18 begins the moment the wheel 29 starts to actuate the davit 11 and this rotation is anti-clockwise and immediately brings the raised portion 95 18^a against the edge of the lever 31 so as to force its end away from the shaft 19 and swing the lever about the pivot 30 (the sub-frame remaining still) until the latch-detent 33 has passed the shoulder 34 in the latch 100 35. This condition remains unchanged while the periphery of the cam-plate 18 rides against the edge of the lever 31 and until the point 18^a passes the end of the lever 31, whereupon the fulcrum provided by the cam 105 18 will have disappeared and immediately its place is taken by the detent 33 so that the spring now tends to turn the lever 31 around the shoulder 34 as a fulcrum and this tends to throw the pivotal connection 30 in 110 the opposite direction and, of course, withdraws the sub-frame and the friction wheel 29 so that all motion ceases in the entire attachment. The sub-frame continues to withdraw until the end of the lever abuts the 115 part 18^a again. This action has resulted in an elevation of the stylus, a swinging of the tone-arm, and a replacement of the stylus. Now, the stylus is in a position to replay the record and will continue to do so until a 120 trip-system comes into effect to release the latch 35 and cause the attachment to re-function in restoring the stylus to its initial position.

The trip system is entirely mechanical in 125 this embodiment and it proposes an element such as the arm H pivoted about the pin I and having a contact surface h adapted to bear up against the arm 37 extending from the latch 35 so as to swing the latch to re- 130

lease the detent 33 on the lever 31. This arm H is frictionally clutched to a trip lever J which extends into a position to be abutted by the sound-box or stylus directly and cause 5 the arm H to operate the latch. As shown by Fig. 3, a spring-washer L compresses the arms J and H' together with just sufficient force to permit of an easy adjustment of the trip-arm J by the hand and yet to transmit 10 without slipping enough pressure to throw the latch. In this way the latch may be caused to operate at any predetermined limit of the stroke of the tone-arm 4, with the result that the tone-arm is uplifted and permitted 15 to swing in an anti-clockwise direction. This movement is in turn limited by a suitable stop.

The adjuster operates to determine the number of times the record will automatically 20 replay, and it comprises an escapement-like device which, after a predetermined number of countings, are released to set a brake against the turn-table. In this embodiment, the parts are composed mainly 25 of sheet-metal and the whole sub-combination is subject to displacement as a unit. Thus, a brake proper consists of a flat strip T with both ends bent at about right angles 30 slidably supported in the opening 22 of the frame and guided by the bent up portion 21, and having its forward end protruding and turned so as to act as a braking surface 42 against the periphery of the turn-table. As shown by Fig. 1, the blank at its other end 35 is laterally extended and carries a post 39 riveted thereto. This post pivotally carries a hand adjustable ratchet 43 having a number of ratchet-teeth 6 that, by an intermittent engagement with the upturned lip 45 of link 16, operate to turn the ratchet-wheel one notch for each stylus lifting cycle. The 40 ratchet-wheel is also provided with a release in the nature of a cut-away portion or slot R. A pin S normally bears against the periphery of the ratchet-wheel and prevents the spring 46 from bodily shifting this sub-mechanism into its braking position; but when this slot R coincides with the pin S, a 45 release is effected and the brake T acts effectively. 50

Without further analysis, the foregoing will so fully reveal the gist of this invention that others can by applying current knowledge readily adapt it for various applications without omitting certain features that, 55 from the standpoint of the prior art, fairly constitute essential characteristics of the generic or specific aspects of this invention, and therefore such adaptations should and are intended to be comprehended within the 60 meaning and range of equivalency of the following claims.

Having thus revealed this invention, we claim as new and desire to secure the following combinations of steps and elements, 65 or equivalents thereof by Letters Patent of the United States.

1. An automatically re-playing phonograph combining a freely-swinging tone-arm; a davit pivoted independently of the 70 axis of said tone-arm and connected therewith adjacent its free end; and means for varying the vertical inclination of the axis of said davit to create a component operative to swing said tone-arm. 75

2. An automatically re-playing phonograph combining a freely-swinging tone-arm having its free end constructed for vertical movement; a davit connected to uplift the free end of said tone-arm; means for pivotally supporting said davit so that the axis thereof will normally incline from the vertical; and mechanism for moving said means to decrease the inclination of said axis so as to uplift the end of said tone-arm 80 and cause the direction of inclination to be such as to produce a swing of said tone arm. 85

In witness whereof, we have hereunto subscribed our names, as attested by the subscribing witnesses.
